UNITED STATES PATENT OFFICE.

PETER M. FABING AND JOHN ACKERMANN, OF ROXBURY, WISCONSIN.

FANNING-MILL.

SPECIFICATION forming part of Letters Patent No. 311,733, dated February 3, 1885.

Application filed July 30, 1884. (No model.)

To all whom it may concern:

Be it known that we, PETER M. FABING and JOHN ACKERMANN, citizens of the United States, and residents of Roxbury, in the county 5 of Dane and State of Wisconsin, have invented certain new and useful Improvements in Fanning-Mills; and we do hereby declare that the following is a full, clear, and exact description of the invention, which enable others 10 skilled in the art to which it appertains to make and use the same, reference being had to the accompanying drawings, which form a part of this specification, and in which—

Figure 1 is a vertical sectional view of a 15 portion of a fanning-mill provided with our stepped screen, and Figs. 2 and 3 are respectively a perspective view of the entire stepped screen and of one of the strips or steps.

Similar letters of reference indicate corresponding parts in all the figures.

Our invention has relation to so-called 20 "stepped screens" for fanning-mills; and it consists in the improved construction and combination of parts of the same, as hereinafter 25 more fully described and claimed.

In the accompanying drawings, the letter A indicates the lower portion of the hopper or chute from which the grain to be cleaned or separated is fed. B indicates the stepped 30 screen, which is in the nature of a stepped inclined screen; and C indicates the separator-screens and D a portion of the fan, all of which usual parts of a fanning-mill may be of any desired construction. The stepped 35 screen is placed above the screens, and above and slightly in front of the fan, and is composed of two inclined side pieces, E E, inclined at an angle of about forty-five degrees, and these side pieces are connected 40 by means of strips or steps F, of sheet metal, bent longitudinally at an obtuse angle, nearly right, and having a swell or corrugation, G, at the bend projecting upon the upper side of the strip, the downwardly-bent portions of the 45 strips facing toward the fan. The outer edges

of the upper portions of the strips or steps project nearly in a line with the inner edges of the strips below them, and it will be seen that when the mill is in operation, and the grain is fed down upon the inclined screen 50 from the hopper the blast from the fan will force the chaff and lighter particles contained in the grain off from the said screen, the blast striking the downwardly-projecting slightly-inclined inner portions of the strips, which 55 will cause the blast to pass up through the screen in a slightly-inclined upward direction, while the heavier good grain will fall through between the edges of the strips down upon the cleaning screens, where it will be 60 subjected to further cleaning. The ends H and I of the two flanges or bent portions of the strips are separated and bent at a right angle to the flanges, whereupon they are secured to the inner sides of the side pieces of 65 the screen, and the longitudinal rib or corrugations at the bend of the strips serve to strengthen the strips and prevent their bending.

Having thus described our invention, we 70 claim and desire to secure by Letters Patent of the United States—

The combination, in a fanning-mill, of two inclined side pieces, and a number of strips or steps bent longitudinally at an obtuse angle 75 formed with corrugations at the bends, and having the ends of the flanges separated and bent at right angles to the flanges and secured to the inner sides of the side pieces, the inner flanges of the steps projecting inclinedly downward, as and for the purpose shown and set forth.

In testimony that we claim the foregoing as our own we have hereunto affixed our signatures in presence of two witnesses.

PETER M. FABING.
JOHN ACKERMANN.
